THOMAS E. DEVOL

၃ၫ

Geo. P. Kinnel, Attorney

UNITED STATES PATENT OFFICE.

THOMAS EARL DE VOL, OF BELGRADE, NEBRASKA.

ELEVATOR.

1,405,301.

Specification of Letters Patent. Patented Jan. 31, 1922.

Application filed September 18, 1920. Serial No. 411,069.

To all whom it may concern:

Be it known that I, THOMAS E. DE VOL, a citizen of the United States, residing at Belgrade, in the county of Nance and State 5 of Nebraska, have invented certain new and useful Improvements in an Elevator, of which the following is a specification.

This invention relates to elevating devices, more particularly to devices of this character employed for elevating a vehicle at one end to dump the load therefrom, and has for one of its objects to simplify and improve the construction and increase the efficiency and utility of devices of this character.

Another object of the invention is to provide a device of this character adapted to be installed in the floor of a building or in a scale platform, without displacing or 20 changing any of the floor joist or other supports.

With these and other objects in view, the invention consists in certain novel features of construction as hereinafter shown and 25 described and then specifically pointed out in the claims, and in the drawings illustrative of the preferred embodiment of the invention.

Figure 1 is a perspective view of the improved device in elevated position with a portion of the floor broken away to show the construction.

Fig. 2 is a transverse section with the parts in lowered position.

Fig. 3 is a side elevation with the floor and adjacent portions in section, and the elevating mechanism in lowered position.

Fig. 4 is a plan view showing the improved device installed in the floor portion 40 of a platform scale.

The improved device is designed to be installed in an opening in the floor of an elevator, store house, the platform of a scale, or like locality, and for the purpose of illustration is shown in Figs. 1, 2 and 3 installed in an opening in a floor indicated conventionally at 10 and supported upon the usual joist indicated at 15.

In Fig. 4 the device is shown embodied in 50 the floor 12 of a conventional platform scale.

The improved device includes main supporting or side plates 13, bolted or otherwise attached at 14 to the confronting faces 55 of a pair of the joist 15 of the floor 10. The joist selected to support the plates may be

any required pair and spaced at any required distance, as the intervening joists are not disturbed by the installing of the plates and the elevating mechanism associated therewith, as illustrated in Fig. 2.

Each of the plates 13 is slotted as shown at 17 near one end and each provided with a bearing 18 to rotatively support a main operating shaft 19.

The platform or support of the elevating mechanism includes a floor or platform 21 supported upon beams or stringers 23, the latter preferably of L bars, as shown.

An opening is formed in the main floor 10 somewhat wider than the spaced defined by the joist 15 to which the plates 13 are attached, as shown in Fig. 2, and the platform 21 fits relatively close in the opening, so that when the elevating mechanism is lowered the platform 21 is flush with the main floor 10, as shown in Figs. 2, 3 and 4, and rests upon all the portions of the joist which extend beneath the opening in the main floor.

Attached to the under faces of the main floor 10 at the ends of the opening are small lugs or supports 24 projecting into the opening and upon which the horizontal webs of the bars 23 rest when the platform 21 is depressed, as shown in Fig. 3, to bear a portion of the downward strain, when the elevating mechanism is in its lower position. The vertical webs of the L bars 23 are slotted at one end, as shown at 25 and corresponding to the slots 17 of the plates 13.

Disposed between the bars 23 and plates 13 are sets of "lazy" tong members 26, the lowermost of the members 26 being pivoted at 27 at one end to the plates 13, while the uppermost of the members 26 are pivoted at 28 to the members 23. The intermediate members 26 are provided respectively with pivots 29 and 30 extending through the slots 17 and 25 and provided with anti-friction rollers 31 and 32 engaging in the slots.

The members 26 are pivotally united where they cross as at 33, and the terminals of the intermediate members pivotally united as at 34.

Connected to the vertical webs of the L bars 23 are rack bars 35 with pinions 36 on the shaft 19 engaged, as shown.

Each of the plates 13 is provided with a strap device 37, each strap device having a bearing 38 to engage the shaft 19 internally of the plate and each strap carrying a bear-

ing roller 39 to engage the untoothed edges of the rack bars, to maintain the rack bars in position and decrease the friction.

Attached to the shaft 19 is a worm gear 40, and supported in a hanger frame 41 attached to one of the joist members 15, is a shaft 42 carrying a worm pinion 43 engaging the worm gear 40.

By this arrangement it will be obvious that when rotary motion is applied to the shaft 42 this motion will be transmitted through the gears 43, 40 and 36 to the shaft 19 and thus move the bars 35 vertically, and elevate or depress the platform 21.

Any suitable power may be employed to rotate the shaft 19, but for the purpose of illustration an electric motor, shown conventionally at 44, is employed for this purpose.

The platform 21 is designed more particularly to receive the forward wheels of a motor truck or other load carrying vehicle and elevate the vehicle at the forward end to cause the dumping of the load from the rear or "tail" end, and operates very effectually for that purpose.

At their lower ends the rack bars 35 are coupled by a stay rod 45, and mounted on this rod are cable guide pulleys 46 while other cable guide pulleys 47 and 48 are suspended in yoke frames 49 and 50 from the plates 13.

Cables 51 are connected respectively at 52 to the plates 13 and passed around the several guide pulleys 46, 49 and 50 and are provided with counter weights 53 at the ends.

By this means a constant upward pulling force is applied to the platform 21 to reinforce the elevating power.

The worm gear 40 and worm pinion 43 coact to lock the bars 35 and platform 21 at any point of elevation, as will be obvious.

The "lazy" tong members serve effectually as diagonal braces to rigidly support the platform and prevent lateral displacement under the strains of the load which it is required to bear.

The preferred embodiment of the invention is disclosed in the drawings and set forth in the specification, but it will be

understood that any modifications within 50 the scope of the claims may be made in the construction without departing from the principle of the invention or sacrificing any of its advantages.

I claim:

1. An apparatus of the class described comprising supporting plates adapted to be attached to floor joist in spaced relation, a platform, beam members connected to said platform, rack bars rigidly connected at one end to said beam members, a power shaft supported in said supporting plates, pinions carried by said shaft and engaging said rack bars, brace members diagonally disposed and pivotally united to each other and pivotally united respectively to the plates and beams, and means for rotating said shaft.

2. An apparatus of the class described comprising supporting plates adapted to be attached to floor joist in spaced relation, a platform, beam members connected to said platform, rack bars connected to said beam members, a power shaft supported in said supporting plates, pinions carried by said shaft and engaging said rack bars, brace members diagonally disposed and pivotally united to each other and pivotally united respectively to the plates and beams, means for rotating said shaft, and counter weights coupled to said rack bars to apply constant 80 upward strain thereto.

3. An apparatus of the class described comprising supporting plates adapted to be attached to floor joist in spaced relation, a platform, beam members connected to said platform, rack bars connected to said beam members, a power shaft supported in said supporting plates, pinions carried by said shaft and engaging said rack bars, brace members diagonally disposed and pivotally united to each other and pivotally united respectively to the plates and beams, a worm gear rotative with said power shaft, a drive shaft, and a worm pinion upon said drive shaft and engaging said worm gear.

In testimony whereof, I affix my signature hereto.

THOMAS EARL DE VOL.
